ANDRÉ BLONDEL, OF PARIS, AND MARCEL TOULY, OF ST.-CLOUD, FRANCE.

MEANS FOR GENERATING HIGH-FREQUENCY CURRENTS.

Application filed May 18, 1921. Serial No. 470,598.

To all whom it may concern:

Be it known that we, ANDRÉ BLONDEL, citizen of the Republic of France, residing at Paris, in the Republic of France, and MARCEL TOULY, citizen of the Republic of France, residing at St.-Cloud, in the Republic of France, have invented certain new and useful Improvements in the Means for Generating High-Frequency Currents, of which the following is an exact and complete description.

This invention relates to a method and means for generating high frequency currents in which a system of valves coupled together are used for the generation of continuous waves for wireless telegraphy and the modulation of these waves for wireless telephony.

The valves connected in parallel serve to set up waves in an antenna circuit and another weaker valve or group of valves serves to excite the main valve by acting on its grid. Additional tiers of valves may be added if desired.

The different valves or groups of valves are connected in such a manner that any one, separately, could not set up persistent oscillations in the antenna, simultaneous action of two valves or groups of valves operating by mutual coupling being necessary for this purpose.

In telephony a microphone may act by mutual induction or by a branch connection by capacity on one of the members of the system of either of the valves in order to detune one of the oscillating circuits or to cause a variation in the degree of coupling.

Under some circumstances a reaction is added between the inductance of the antenna and the grid of one of the valves to diminish the damping of the antenna. It is to be understood, however, that such reaction must be kept within certain limits wherein the said reaction is insufficient to give rise, by itself to oscillations in the antennæ.

In the drawings herewith:—

Fig. 1 shows the general principles of the invention in diagrammatic form.

Fig. 2 is a diagrammatic view of the system with three tiers of valves.

Fig. 3 is a diagrammatic view of the system with a special device for improving the modulation process and obtaining a more powerful action by a microphone.

Fig. 4 shows the application of the system in a transmitting station for use in connection with alternating current.

Fig. 5 shows a wireless telephone station with duplex connections utilizing the principles set forth in the preceding figures.

In the drawings the following reference letters are used:—

A¹ indicates a relay valve.
A² indicates a working valve.
G indicates a grid.
P indicates a plate.
L indicates an inductance.
C indicates a condenser.
La and Ca indicate the inductance and capacity of the antenna.
B indicates a battery.
Bc indicates a heating battery.
Bl indicates a battery for making the grids negative.
t indicates a transformer.
T is an earth connection.
γ is a coupling condenser of small impedance.
Z is the impedance of the coupling.
r is a rheostat in the heating circuit of the filament.
R is a large resistance to static charges.
Lm is a mutual induction winding.
M is a microphone.
Bm is a microphone battery.

A¹' and A²' are differential valves for modulation.

Arrows across a condenser or winding show that they are adjustable.

In the installations shown herewith a rheostat of high resistance has been provided for discharging in the usual manner, the grids on the filaments so as to prevent their taking too heavy negative charges during the oscillations. In some cases, this rheostat may be replaced by the internal resistance of a valve, the grid of which is subjected to the action of a microphone.

A microphone is included in all the arrangements shown for the reason that they all lend themselves effectively to telephony, but if desired, for telegraphic purposes a signaling key could be substituted for the microphone, the couplings being arranged so that transmission is interrupted by the closing of the signaling key. In some forms the working valve and its oscillating circuit are made dependent on the switch and the

relay valve or group has a power equal to the losses occurring in the grid circuit of the valve or valves. It is desirable to reduce this power for economical reasons and also 5 to permit of the modulation of a high power in the working valves and the intensity of the current given by the microphone.

In Fig. 1 the system is shown with the grid of the working valve A^2 coupled 10 through the plate inductance L^m with the antenna inductance. The said valve and its circuit may be adjusted slightly below the point of oscillation. By modulation of the circuit through the intermediary of a microphone connected at M to induction coil $L'm$, the circuit may be set into a state of oscillation. 15

In Fig. 2 is shown an arrangement with two relay valves arranged in cascade the 20 connection between valves A_1 and A'_1 being made through the circuit $L C$, and the connection between the relay valve A'_1 and A_2 being made through the transformer T . The damping of the antenna is reduced by 25 the reaction of the capacity C_0 , the working valves being arranged slightly below the point of continuous oscillation and the microphone M being coupled to the oscillatory circuit through a condenser C^e .

30 This invention is not limited to the use of two relay valves in cascade, as for high power stations several valves could be used either in cascade,—or in parallel,—or in cascade-parallel, the connections between the valves consisting of any of the usual known means.

The reaction for the reduction of the damping may be produced between the plate circuit and the working valves and any one 40 of the relay valves. To effect this between the antenna and the first valve the left hand plate of the condenser C_0 is connected to the grid of A_1 . To reduce the damping by the action of the grid of A_1 , a mutual induction coil (not shown) could be introduced between the two points a and b of the circuit of the said grid (Fig. 2) which coil is arranged as is Lm in close proximity to the inductance L^a so as to obtain a suitable 45 phase.

50 In Fig. 3 there is shown a system in which a microphone acts as a modulator in a coupled valve generator. The high frequency generator (not shown) induces in the plate circuits of the valves electro-magnetic force the amplitude of which will be at most equal to the electro-magnetic force of the battery B_1 by a suitable choice of either the battery or the transformer. A 55 battery B^3 in the connection of the neutral point may be employed to render the grids negative, and B^e is the battery for heating the filaments. This heating may be rendered equal by the contact K connected to the battery along the rheostat r , and thereby the 60

currents may be equalized when there is no speech into the microphone.

In Fig. 4 the system shown may be used in a transmitting station the tubes being for use in connection with alternating current. 70 A^1 is the relay valve, A^2 is the working valve, L^1 , L^2 , L^3 and L^4 are inductances, T is the ground, γ^2 is a coupling condenser of small impedance, R^1 is a resistance to static charges, t^1 , t^2 , t^e are transformers, and C^1 75 and C^2 are condensers.

A duplex arrangement for wireless telegraphy is shown in Fig. 5, the known generating and modulating arrangements being represented by rectangles, and the figure 80 showing how they act on a generator with three amplifying stages in which the return action acts on the grids of the second tier of valves. D is a small generator of the usual type; M is a modulator; A^1 is a relay valve whose grid is acted upon by the said modulator, and A^2 is a group of valves in 85 parallel and forming a second amplifying stage, and A^3 is a second group of more powerful valves arranged in parallel and constituting a third stage of large output. Three valves of a high and low frequency amplifier are indicated by the reference letters, a^1 — a^2 and a^3 . 90

We claim:—

1. In the generation of high frequency alternating currents for radio signaling by means of thermionic tubes, two thermionic units comprising a power or working unit and a relay unit, the working unit being first adjusted in a nearly oscillating condition by retroactively coupling its input and output circuits and the state of oscillation being then obtained by once more retroactively coupling the same circuits through 100 the relay unit.

2. A high frequency vacuum tube generator comprising in combination, an oscillating circuit, a power or working thermionic unit connected thereto, a relay thermionic unit with its output circuit connected to the input circuit of the said working unit, means for retroactively coupling the input and output circuit of the first unit through the second one, of an amount sufficient 110 to keep the system oscillating and means for varying the said amount according to the rhythm of signals.

3. A high frequency vacuum tube generator comprising in combination an oscillating circuit, a power or working thermionic unit connected thereto, a first reaction coupling between the circuits of the said unit of insufficient magnitude to keep the unit oscillating, a relay unit the output circuit of which is connected to the input circuit of the said working unit, a second reaction coupling between the output and input circuits of the working unit through 120 the relay unit of an amount sufficient to 125 130

keep the system oscillating and means to vary the said second reaction coupling according to the rhythm of signals.

4. A high frequency vacuum tube generator comprising in combination an oscillating circuit, a power or working thermionic unit, connected thereto, said unit consisting in a vacuum tube a first reaction coupling between the circuits of the said unit, of a magnitude insufficient to bring the unit into oscillation a relay unit, the output circuit of which is connected to the input circuit of the

said working unit, a second reaction coupling between the input and output circuit of the working unit through the relay unit of a magnitude sufficient to keep the system oscillating and means to vary the said second reaction coupling according to the rhythm of signals.

In witness whereof we have hereunto signed our names this 3rd day of May 1921.

ANDRÉ BLONDEL.
MARCEL TOULY.
